UNITED STATES PATENT OFFICE

2,474,081

ONE-PERSON SEESAW

Morris D. Wolf, Chicago, Ill.

Application August 17, 1945, Serial No. 610,969

3 Claims. (Cl. 272—55)

1

Objects of the invention reside in the provision of a novel, rugged and attractive toy of the bouncing hobbyhorse type, which is constructed mainly of flat bar metal stock, such as spring steel, which is able to accommodate and to function satisfactorily with riders of widely differing weights, and which provides a securing structure for adequately securing the spring bar, seat and head piece of the device together while permitting the head piece to be constructed of relatively thin wood or the like without liability of the head piece breaking.

The invention will be better understood by reference to the accompanying drawing forming a part hereof and in which—

Figure 1 is a perspective view of a toy embodying my invention;

Figure 2 is a partial section substantially on the line 2—2 of Figure 1;

Figure 3 is a partial sectional view substantially on the line 3—3 of Figure 1;

Figure 4 is a partial sectional view substantially on the line 4—4 of Figure 1; and

Figure 5 is a section substantially on the line 5—5 of Figure 1.

Referring to the drawing, two base members of flat metal stock, preferably spring stock, are respectively designated at 1 and 2. These have their widths disposed vertically, and bolts 3 pass through registering apertures, respectively designated at 4 and 5, through the base members, as best shown in Figure 4, and secure the same together forwardly in face-to-face and correspondingly lineally extending relation. These base members are oppositely curved lineally and facewise and away from each other, as respectively designated at 6 and 7 in Figure 1, rearwardly from the region 8 at which they are secured together by the bolts 3 whereby they diverge horizontally from the region 8 to form the base of the device.

The base member 2 terminates immediately forward of the region 8, and the base member 1 extends and is twisted forwardly of the region 8, as designated at 9 and best shown in Figure 4, to dispose the width of its forward portion horizontally as designated at 10. This forward portion is curved lineally and facewise thereof upwardly into a part coil 11.

A spring bar 12 of flat metal spring stock, see Figure 1, has its width disposed horizontally and has its forward end portion curved lineally and facewise thereof and downwardly therefrom into the form of a coil 13 engaging underneath the adjoining portion of the spring bar as designated

2

at 14. The spring bar coil 13 is seated in the part coil 11 of the base with the spring bar 12 extending from the top of the spring bar coil upwardly and rearwardly over the base. A bolt 15, passing through registering apertures, respectively designated at 16 and 17 in Figure 5, through the part coil 11 and spring bar coil 13 in the region of the extending end of the part coil 11, secures the spring bar coil in the part coil with the spring bar extending upwardly and rearwardly over the base as aforesaid.

A flat seat 18 of thin wood or like material is arranged in the region of the rear end of the spring bar 12 and has a flat longitudinal extension 19 extending longitudinally of and overlying the spring bar in face-to-face relation therewith. See Figures 1 and 2. A flat head piece 20, shown in the form of a horse's head, is arranged above the seat extension 19 and has its plane disposed normal to the planes of and longitudinally of the extension and spring bar and has its lower edge engaging downwardly on the extension. As so arranged, the spring bar, seat extension and head piece are secured together by means of duplicate bolt structures spaced longitudinally of the extension and spring bar, one of these bolt structures being described below with particular reference to Figure 2.

A headed screw 21 extends upwardly through 30 registering bores, respectively designated at 22, 23 and 24, through the spring bar 12, the seat extension 19 and in the head piece 20, of which the bore 24 of the head piece is disposed parallel to the faces thereof, and a nut 25 is threadably 35 engaged by the screw 21 and is disposed in an aperture 26 extending facewise through the head piece and intersecting the bore 24 of the head piece. Thus is provided securing means for adequately securing the spring bar, the seat extension and the head piece together in their aforesaid relation which is not liable to cause breakage of the relatively thin head piece.

A transverse handle bar 27 is mounted upwardly on the head piece 20 to be grasped by a child 45 seated on the seat 18, and a foot bar 28 is adjustably secured on the intermediate portion of the spring bar, see Figures 1 and 3, by means of a U-shaped clamp member 29 embracing the spring bar and passing through the foot bar, and 50 thumb screws 30 screwthreaded on the legs of the clamp member to clamp the foot bar on the spring bar.

A child, seated on the seat 18 and grasping the handle bar 27 and having his feet resting on the 55 foot bar 28 may bounce by reason of the resilien-

cy of the structure, the rearwardly diverging base members 1 and 2 affording adequate transverse footing at the rear of the device and below the child on the seat.

While the spring bar 12 affords the major resiliency of the device, the part coil 11 and the spring bar coil 13 add further resiliency and serve to distribute the bending stress on the spring bar and serve to stiffen the spring bar in the region of the greatest stress thereon. Preferably, the part coil and the spring bar coil are slightly separated below the securing bolt 15, as designated at 31, to permit freedom of action of the part coil and spring bar coil, the spring bar coil resting on the part coil at the bottom thereof. The spring bar 12 tends to wrap about the spring bar coil 13, the spring bar coil tends to expand horizontally and to contract vertically, and the part coil 11 tends to decrease its radius as weight is applied on the seat, with the result that the device is able to accommodate and function satisfactorily with a wide range of weights on the seat.

While I have thus described my invention, I do not wish to be limited to the precise details described, as changes may be readily made without departing from the spirit of my invention, but having thus described my invention, I claim as new and desire to secure by Letters Patent the following:

1. In a toy, the combination of a base comprising two base members of flat metal stock having their widths disposed vertically and secured together forwardly in face-to-face and correspondingly linearly extending relation and diverging horizontally and rearwardly from the region at which they are secured together to form the base, one of said base members extending and being twisted forwardly of said region to dispose the width of its forward portion horizontally, and a spring bar of flat metal spring stock having its width disposed horizontally and secured on said forward portion of said forwardly extending base member in face-to-face relation therewith and extending rearwardly and upwardly over said base and carrying a seat rearwardly thereon.

2. In a toy, the combination of a base comprising two base members of flat metal spring stock having their widths disposed vertically and secured together forwardly in face-to-face and correspondingly linearly extending relation and diverging horizontally and rearwardly from the region at which they are secured together to form the base, one of said base members extending and being twisted forwardly of said region to dispose the width of its forward portion hori-

zontally and having said forward portion curved linearly and facewise thereof upwardly into a part coil, and a spring bar of flat metal spring stock having its width disposed horizontally and carrying a seat rearwardly thereon and having its forward end portion curved linearly and facewise thereof and downwardly therefrom into the form of a coil engaging underneath the adjoining portion of the spring bar, said spring bar coil being seated in said part coil with said spring bar extending from the top of said spring bar coil upwardly and rearwardly over said base and being secured with said part coil in the region of the extending end of said part coil with said spring bar extending as aforesaid.

3. In a toy, the combination of a base comprising two base members of flat metal spring stock having their widths disposed vertically and bolts passing through registering apertures through said members and securing said members together forwardly in face-to-face and correspondingly linearly extending relation and said base members being oppositely curved linearly and facewise and away from each other rearwardly from the region at which they are secured together whereby they diverge horizontally from said region to form the base, one of said base members extending and being twisted forwardly of said region to dispose the width of its forward portion horizontally and having said forward portion curved linearly and facewise thereof upwardly into a part coil, a spring bar of flat metal spring stock having its width disposed horizontally and carrying a seat rearwardly thereon and having its forward end portion curved linearly and facewise thereof and downwardly therefrom into the form of a coil engaging underneath the adjoining portion of the spring bar, said spring bar coil being seated in said part coil with said spring bar extending from the top of said spring bar coil upwardly and rearwardly over said base, and a bolt passing through registering apertures through said part coil and said spring bar coil in the region of the extending end of said part coil and securing said spring bar coil in said part coil with said spring bar extending as aforesaid.
